DESIGN FOR A TIRE

Arthur Balthazar, Chicopee Falls, Mass., assignor
to The Fisk Rubber Corporation, Chicopee
Falls, Mass., a corporation of Delaware

Application June 26, 1935, Serial No. 57,414

Term of patent 14 years

To all whom it may concern:

Be it known that I, Arthur Balthazar, a citizen of the United States, residing at Chicopee Falls, in the county of Hampden and State of Massachusetts, have invented a new, original, and ornamental Design for a Tire, of which the following is a specification, reference being had to the accompanying drawing, forming part thereof.

Fig. 1 is a plan developed view of a portion of a tire showing my new design;

Fig. 2 is a transverse radial section of a tire taken substantially on line 2—2 of Fig. 1; and

Fig. 3 is a perspective view of a tire showing my design, a section being illustrated in solid line.

I claim:

The ornamental design for a tire as shown.

ARTHUR BALTHAZAR.
